UNITED STATES PATENT OFFICE

1,971,193

POLYPHASE OSCILLATION GENERATOR

Elmer D. McArthur, Schenectady, N. Y., assignor
to General Electric Company, a corporation of
New York

Application May 20, 1930, Serial No. 454,170

7 Claims. (Cl. 250—36)

My invention relates to generators of polyphase high frequency electromotive force and it has for its object to provide a generator of the type indicated which is of more simple and economical construction than those of the prior art.

A further object of the invention is to provide an oscillation generator of the type indicated employing a single electron discharge device of simple construction through action of which polyphase oscillations are produced upon the circuits associated with the electrodes thereof. Still a further object of the invention is to provide an arrangement whereby an electron discharge device of the magnetic field divided, or split, anode type, may be utilized for the production of polyphase high frequency oscillations, the anode structure of the discharge device being divided in accordance with the number of phases to be produced.

Still a further object of the invention is to provide a system in which polyphase oscillations are produced through action of a single electron discharge device and which at the same time, avoids the use of a grid structure within the discharge device and coupling circuits between the different anodes and their corresponding grids to produce a regenerative action sufficient to sustain oscillations.

Another object of the invention is to provide a system of the type indicated which is particularly adapted to produce polyphase oscillations of short wave length. The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Figs. 1, 2 and 3 represent different embodiments of my invention.

Referring to Fig. 1 of the drawing, I have shown therein an electron discharge device 1 having an anode structure in the form of a cylinder, this cylinder being divided longitudinally thereof into a number of anode segments 2, 3, 4. The number of segments of the anode structure corresponds to the number of phases of the oscillations to be produced. A cathode 5 is shown extending longitudinally of the discharge device along the axis of the anode cylinder. This cathode is arranged to be heated by means

of a source of electromotive force 6 through a control resistance 7. A field winding 8 is arranged about the electron discharge device and is energized from a source of unidirectional electromotive force 9 through a control resistance 10, the winding being so disposed about the discharge device that the lines of force extend within the anode cylinder and substantially parallel with the cathode.

The circuit arrangement wherein the polyphase oscillations are produced, comprises a plurality of inductances 11, 12 and 13. Since as shown in the drawing the system is adapted to produce 3 phase electromotive force, three of these inductances are shown, these inductances being connected in Y, the outer terminals of the Y being connected to the anodes 2, 3 and 4 respectively, and the neutral point of the Y being connected through a source of unidirectional potential 14 to the cathode. By means of this source of potential all of the anodes are maintained at a constant average positive unidirectional potential with respect to the cathode.

Connected between the outer terminals of the Y are a plurality of condensers 15, 16 and 17. These condensers, as will be apparent from the drawing, are connected in parallel with the internal capacity of the discharge device between adjacent electrodes to which they are connected. Accordingly when the device is operated at very high frequencies these condensers may be omitted. In fact, at very high frequency the inductances 11, 12 and 13 may comprise merely the inductances of the conductors leading to the anodes.

As thus arranged it will be seen that the circuit comprises a plurality of oscillatory circuits, one of which comprises the inductances 11 and 12 and the condenser 15; another comprising the inductances 11 and 13 and the condenser 16; and the third comprising the inductances 12 and 13 and the condenser 17.

If we assume that the cathode of the discharge device is heated to incandescence, that the source of anode electromotive force 14 is adjusted to a value suitable for operation, and that the field intensity is then increased, it will be found that over a range of field intensities oscillations will be excited in the circuits above described. If we assume that prior to the initiation of these oscillations electrons are flowing from the cathode to each of the anodes in an extent sufficient to cause equal currents to flow in the inductances 11, 12 and 13, and then through action of two of the anodes, as for ex-

- ample anodes 2 and 3, oscillations are excited in one of the above circuits, as for example the circuit 11, 12, 15 thereby causing one of the anodes 2, 3 to become more positive and the other less positive, it can readily be understood that the current conditions within the discharge device will be so disturbed as to cause a change of current in inductance 13, thereby exciting oscillations in the other two oscillatory circuits.
- 10 I have found that these oscillations are sustained in the various circuits and have a definite polyphase relation with respect to each other.

- The arrangement shown in Fig. 2 is similar to that shown in Fig. 1 with the exception that 15 the inductances 11, 12 and 13 are connected in delta rather than in Y. In this case the mid-points of all of the inductances are connected together and to the positive side of the source of potential 14. Connected in parallel with each 20 of the inductances 11, 12 and 13 are the condensers 15, 16 and 17, the oscillatory circuits in this case comprising the elements 11, 15; 12, 16; and 13, 17. Each of these circuits is resonant at the frequency of the oscillations to be 25 produced and connected as shown oscillate in polyphase relation. The arrangement shown in Fig. 3 differs from that shown in Fig. 1 only in that the inductances 11, 12 and 13 are arranged upon a suitable non-conducting frame 30 18 which suitably may be of cylindrical form.

- The polyphase oscillations produced in the circuits may be supplied to a suitable load circuit by means of any desired and well known form of coupling. In Fig. 1 the inductances 11, 35 12 and 13 are shown as comprising the primary windings of single phase transformers, the secondary windings of these transformers being connected in Y and connected to a suitably polyphase load circuit 19. It will of course be understood that the secondary windings may be connected either in Y or in delta.

- In Fig. 3 I have shown each phase of the load 45 circuit 19 coupled to a corresponding phase of a polyphase oscillatory circuit through a suitable coupling condenser 20.

- While in each of the figures of the drawing I have shown an electron discharge device having 50 three anodes and which is thereby adapted in association with the circuits described to produce three phase oscillations, it will of course be understood that there may be any greater number of anodes in accordance with the number of phases of the oscillations which it is desired to produce.

- 55 It will thus be seen that the system in accordance with my invention possesses great advantages in the simplicity of the arrangement in that the oscillations are excited through action of the magnetic field upon the electrostatic conditions within the discharge device as distinct from any regenerative arrangement employing grids within the discharge device and associated anode to grid coupling circuits. Thus in the 60 system described the anodes are adjacent to the cathode, there being no grid structure interposed between the cathode and anodes. Further, it has been found that discharge devices of the type described are capable of producing oscillations of short wave length. Thus the system is particularly adapted for use in short wave 65 radiation systems particularly in connection with directive beacon systems such as may be utilized for directing aircraft, where it is desired to radiate directionally in three or more directions

rather than in two directions as in present practice.

While I have shown particular embodiments of my invention, it will of course be understood that I do not wish to be limited thereto since many modifications may be made both in the circuit arrangement and in the instrumentalities employed, and that I therefore contemplate by the appended claims to cover all such modifications as fall within the true spirit and scope of my invention.

What I claim as new and desire to secure by Letters Patent of the United States is:

1. The combination, in a system for producing polyphase high frequency electromotive force, a polyphase circuit, means including a single electron discharge device having at least three electrodes for exciting oscillations in said circuit, each of said electrodes being included in a corresponding phase of said circuit and means for producing a magnetic field within said discharge device to control the action thereof thereby to cause polyphase high frequency electromotive force to be produced in said polyphase circuit, said magnetic field being unidirectional during 100 the production of said polyphase electromotive force.

2. The combination, in a system for producing polyphase electromotive force, a polyphase circuit, means including a single space discharge 105 device for exciting oscillations in said circuit, said space discharge device comprising a number of anodes greater than two, and a cathode, said anodes being arranged about said cathode and each anode being connected to one phase of said 110 polyphase circuit, means to produce a magnetic field between said anodes whereby polyphase oscillations are produced in said polyphase circuit, and means whereby the frequency of said polyphase oscillations is dependent upon the 115 frequency characteristics of said polyphase circuit.

3. In combination, an electron discharge device, having a centrally located cathode and a number of anodes greater than two disposed 120 about said cathode, means for producing a unidirectional magnetic field between said anodes and cathode, means for supplying a positive potential to each of said anodes with respect to said cathode, a polyphase circuit connection 125 including said anodes and cathode whereby when said magnetic field is produced between said electrodes alternating electromotive force is produced between each anode and the cathode, and the electromotive forces on the different anodes 130 bear a polyphase relation to each other, and means whereby the frequency of said polyphase electromotive forces is dependent upon the frequency characteristic of said polyphase circuit.

4. In combination, an electron discharge device having a number of anodes greater than two, and a cathode, said anodes being disposed 135 about said cathode in the form of a cylinder, means for producing a magnetic field within said cylinder and extending longitudinally thereof, a polyphase circuit arranged to oscillate in each phase, and each phase being connected to one of said anodes whereby polyphase oscillations are excited in said circuit through action of said discharge device.

5. The combination, in a system for producing polyphase high frequency electromotive force, an electron discharge device having a centrally arranged cathode and a number of anodes greater than two arranged about said cathode, a poly- 150
